UNITED STATES PATENT OFFICE.

CECILE LAFITTE, OF NEW YORK, N. Y.

LAMP.

1,333,428.

Specification of Letters Patent. Patented Mar. 9, 1920.

Application filed June 5, 1919. Serial No. 301,890.

To all whom it may concern:

Be it known that I, CECILE LAFITTE, a citizen of France, and a resident of the city of New York, borough of Manhattan, in the county and State of New York, have invented a new and Improved Lamp, of which the following is a full, clear, and exact description.

This invention relates to a lamp, and aims more particularly to provide a device of this nature which shall be capable of being utilized as a bed light or which may be shaded so as to provide a night light, and which may be adaptable to the application of an ornamental figure to its framework so that the finished product may present a lamp which is highly ornamental and pleasing to the eye, as well as practical in all particulars.

20 A further object of this invention is the provision of a framework for a lamp which may have secured to it a socket positioned in such a manner that different globes may be readily substituted one for the other and 25 a new globe instantly substituted for a broken one.

20 A still further object of the invention is the provision of a framework which shall be especially adapted for mounting a representation of a human figure, together with 30 its associated clothes.

30 A final object of the invention is to provide a lamp incorporating as few parts as is consistent with strength.

35 Having these objects in mind, attention is invited to the accompanying drawings which represent one practical embodiment of my invention, and in which—

40 Figure 1 is a front elevational view of my improved form of lamp with part of the clothes of the applied figure removed;

Fig. 2 is a plan view of the supporting framework; and

45 Fig. 3 is a sectional view taken through the globe socket and the supporting frame therefor.

50 In these figures, like reference numerals designate similar parts, and the reference numeral 1 indicates rods which have their lower ends coiled around a ring 2, or otherwise secured thereto, and extend thence upwardly and inwardly toward a common center, their upper ends being secured by any convenient method to an upper ring 3.

55 As shown, the rods 1 and rings 2 and 3 are preferably wrapped with cloth, so that

the danger incident to rotting of the housing cloth may be eliminated. Also, by this wrapping, the danger of the housing cloth catching any of the projecting parts of the 60 rods or rings is eliminated.

Positioned below the upper ring 3, and suspended therefrom by means of supporting wires 4, which are adapted to be looped around the ring 3 and the upper ends of the 65 rods 1, is a socket 5, which is formed with openings 6 through which the wires 4 are adapted to pass and to have their outer ends preferably looped around one of the rods 1 adjacent its end portion. In connection with 70 this structure, I wish it understood, however, that any suitable supporting means for a socket may be utilized, but I have found, keeping simplicity and, consequently, economy in mind, that the above suspending 75 means is preferably adaptable in connection with the socket.

Resting upon the ring 3 is the base 7 of a doll 8, preferably of china, representing a human figure. This base is preferably provided with openings 9, extending from its side walls through to its lower face, and wires 10, or other suitable lacing means, are adapted to be passed through the openings 9 and around the upper ring 3 whereby to 85 firmly secure the doll 8 in position upon such ring.

In connection with the lamp which I intend to construct, I provide a dress 11 which may be entirely closed and which gives the 90 doll the appearance of wearing a hoop skirt.

A wire 12, which may be provided with a switch (not shown), is connected with the socket 5 for supplying electric current, and a globe 13 is applied to the socket for 95 illuminating purposes.

In operation it will now be appreciated that upon current flowing through the socket 5 to the attached globe 13, a light will be produced within the dress 11. The 100 globe 13 may be tinted as desired, and the dress 11 may be produced in any number of color designs, which will be extremely pleasing to the eye and produce a beautiful color effect which may blend harmoniously with 105 the general furnishings of the room in which it is adapted to be placed.

If it is desired to utilize the lamp as a reading lamp, instead of as a night lamp, the same may be used by an occupant of the 110 room without having the light disturb any one else, by either lifting a portion of the

dress 11 upwardly along the frame, or having the dress capable of being parted and rotate the entire figure so that the light shines in the general direction desired.

5 It is to be appreciated that any number of modifications of construction may be resorted to without in the least departing from the scope of my invention.

Having thus described my invention, I 10 desire to claim:

1. A lamp, including an upper ring, a larger lower ring, rods extending between such upper and lower rings, a socket suspended below and secured to such upper 15 ring, a doll secured to such upper ring and above the same, and a dress extending from said doll downwardly to the lower ring and around the rods.

2. A lamp, including an upper ring, a larger lower ring, rods extending between such upper and lower rings, a socket suspended below and secured to such upper ring, a doll, representing the upper portion 25 of a human figure, secured to such upper ring and above the same, and a dress extending from said doll downwardly to the lower ring and around the rods.

3. A lamp, including an upper ring, a lower ring of larger diameter than the upper ring, rods extending between such upper and lower ring, a socket having openings extending through its base, looped wires adapted to be passed around the upper ring, said wires extending downwardly and 35 through the openings in the base of the socket and having their outer ends secured to such rods adjacent their upper ends.

4. A lamp, including an upper and a

lower ring of larger circumference than the upper ring, rods extending between such upper and lower rings, a lamp suspended from such upper ring, a doll, representing a human figure, positioned above said upper ring, said doll being formed with a base portion provided with openings extending 45 from its outer face through to its lower face, and securing wires extending through such openings and around the upper ring adapted to retain the doll in applied position.

5. A lamp, including an upper ring and a lower ring, supporting means extending between such upper and lower rings, a socket suspended below and secured to the upper ring, and a doll figure arranged 55 above the upper ring, the dress of said doll extending downwardly to a point adjacent the lower ring.

6. A lamp, including a doll, means for supporting such doll, and a lamp suspended below the body portion of the doll, the dress of such doll being normally adapted to inclose such lamp.

7. A lamp including a framework, a socket attached to the same, a doll figure 65 supported by said framework, the dress of the doll being adapted to encircle the frame and to be held in extended position thereby.

8. A lamp including, an upper ring and a lower ring, supporting means extending between such upper and lower rings, a socket attached to one of said rings, and a doll figure arranged above the upper ring, the dress of said doll extending downwardly to a point adjacent the lower ring.

CECILE LAFITTE.
